AWNNG WITH ADJUSTABLE LOUVERS

Joseph S. Phillips, Fort Worth, Tex.

Application June 29, 1949, Serial No. 101,995

1 Claim. (Cl. 20—57.5)

1

This invention relates to awnings for windows, doors, and the like, and has reference to improvements in ventilation awnings.

An object of the invention is to provide an awning having easily adjusted movable louvers thereon and which louvers can be fixedly secured at various angles so as to admit desired amounts of sunlight.

Another object of the invention is to provide a sturdy construction in an awning having adjustable louvers forming a part thereof.

A further object of the invention is to provide an adjustable louver arrangement for awnings, and whereby said louvers may be easily and conveniently adjusted by crank means within the building where the awning is located.

These and other objects of the invention will become apparent from the following description and the accompanying drawings, wherein:

Figure 1 is a perspective view of the awning attached to the window frame of a house, and showing the latter partly broken away so as to show the location of the operating crank.

Figure 2 is a vertical sectional view of the awning illustrated in Figure 1 and particularly showing the mechanism for operating or tilting the movable louvers, together with pawl means for securing said louvers in any desired position.

Figure 3 is an enlarged broken sectional view of the upper portion of Figure 2, and particularly showing the means employed for tilting louvers, and

Figure 4 is an enlarged broken sectional view illustrating the relative position of the actuating bar, one of the cranks operated thereby, and the location of the crank relative to one of the end plates of the awning.

The numeral 10 designates a pair of spaced vertical end plates substantially in the form of a quarter of a circle; however, it is to be understood that within the scope of the invention, these end plates may be in other forms, such as triangular, or shaped to accommodate casement windows. The end plates 10 are joined at their upper and lower corners by horizontal frame members 11 and 12 for supporting a structure on the outside of a building opening frame 13. The outer and upper edges of the end plates 10 are respectively inwardly flanged, as at 14, to support a former 15 of Z stock, as particularly shown in Figure 4. The depending webs or flanges of the formers 15 rotatably receive the ends of transverse parallel rods 17, the latter having cranks 18 formed at corresponding ends thereof for piv-

2

otal connection with an actuating bar 19. In the illustrated form of the invention, the actuating bar 19 is arcuate in shape so as to conform with the arcuate contour of the adjacent end plate 10.

Transverse louvers 20 are secured along corresponding longitudinal sides to the rods 17, said louvers being secured thereon by means of bending said corresponding edges around the lengths of said rods between the webs 16 of the formers 15. The entire construction, where possible, is preferably welded, although rivets, screws and the like may be used if desired.

A horizontal shaft 21 is supported parallel with the inner surface of the end plate 10 adjacent the actuating bar 19. The shaft 21 is supported at one end by means of a bracket 22 secured to the inner surface of the last referred to end plate 10, whereas the other end of said shaft 21 is supported in a bearing 23 mounted on and near the inner edge of said end plate. The shaft 21 thence extends through a vertical frame member 24 and through an opening (not shown) in the frame 13 of the building. A crank 25 is secured to the last referred end of the shaft 21.

A worm gear 26 is secured on the shaft 21 near the bracket 22 and is arranged for coaction with a segment gear 27 having an integral upwardly extending arm 28. The segment gear 27 is pivotally supported by the end plate 10 by means of a pin 27a. The upper end of the arm 28 is pivotally connected with one end of a link 29, and the other end of said link is pivotally connected with the actuating bar 19 near its upper end. A hood 30 of sheet material is secured across the upper ends of the end plates 10 and extends outwardly so as to cover the upper inner edge of the uppermost louver 20. As particularly shown in Figures 2 and 3, the hood 30 is upwardly flanged, as at 31, where it fits against the building frame 13, and is upwardly and outwardly flanged, as at 32, where it covers the inner edge of the uppermost louver 20.

A vertically projecting plate 33 is secured to the vertical surface of the lower cross member 12 at the end thereof adjacent the end plate 10 carrying the segment gear 27, said plate being arranged for engaging notches 34 in the lower edge of a pawl 35. The end of the pawl 35 opposes the notches 34 and is pivotally secured to the lower end of the actuating bar 19.

In operation, the pawl 35 is raised from the holding plate 33, and by operating the crank 25, which thereby actuates the shaft 21, worm gear 26, segment gear 27, and link 29, the actuating

bar 19 is moved upwardly or downwardly. By reason of connection of the actuating bar 19 with the cranks 18, the louvers 20 may be raised or lowered simultaneously for admitting or excluding sunlight. By engaging the pawl 35 on the holding plate 33 and engaging one of the notches 34 on the latter, the louvers 24 may be secured and maintained in the angular position adjusted by the crank 25.

The described form of the invention may be made in many ways within the scope of the following claim:

What is claimed is:

An awning comprising a pair of spaced vertically disposed end plates each having downwardly and outwardly directed upper edges, a depending vertically disposed flange member supported by each of said end plates and inwardly positioned with respect to the latter, spaced parallel rods extending through and pivotally sup-

ported by said vertically disposed flanges, louvers secured to said rods between said flanges, cranks formed at corresponding ends of said rods, an actuating bar pivotally connected with said cranks, a segment gear linked with said actuating bar, and gear means supported and arranged for coaction with said segment gear.
